US00D828822S

(12) **United States Design Patent** (10) Patent No.: **US D828,822 S**
(45) Date of Patent: **** Sep. 18, 2018**

(54) **STRAP HOLDER**

(71) Applicant: **Oculus VR, LLC**, Menlo Park, CA (US)

(72) Inventors: **Scott Andrew Dallmeyer**, Seattle, WA (US); **Shane Michael Ellis**, Bellevue, WA (US); **Peter Wesley Bristol**, Seattle, WA (US); **Mauricio Romano**, Redmond, WA (US)

(73) Assignee: **Oculus VR, LLC**, Menlo Park, CA (US)

(**) Term: **15 Years**

(21) Appl. No.: **29/603,909**

(22) Filed: **May 12, 2017**

(51) LOC (11) Cl. **14-03**
